Patented Feb. 13, 1912.

UNITED STATES PATENT OFFICE.

WILLIAM R. TURNER, OF WALLACE, IDAHO.

PIANO-PROTECTOR.

1,017,608.

Specification of Letters Patent. Patented Feb. 13, 1912.

Application filed May 11, 1910, Serial No. 560,698. Renewed September 14, 1911. Serial No. 649,480.

To all whom it may concern:

Be it known that I, WILLIAM R. TURNER, a citizen of the United States, residing at Wallace, in the county of Shoshone and 5 State of Idaho, have invented certain new and useful Improvements in Piano-Protectors, of which the following is a specification.

This invention relates to shields for protecting the lower panel of a piano in order 10 to prevent the same from being scratched or marred by the feet of the player, the object of said invention being to provide a protecting device which may be readily placed in 15 position and which, when the instrument is not in use may be conveniently closed.

With these and other objects in view, the present invention consists in the combination and arrangement of parts which will be 20 hereinafter more fully described and particularly pointed out in the appended claims, it being understood that the changes in the specific structure shown and described may be made within the scope of the claims without departing from the spirit of the invention. 25

In the drawings: Figure 1 is a front elevation of a piano showing the shield in position. Fig. 2 a view of the device detached, 30 and Fig. 3 a view showing the device in its closed position.

In the drawing: 10 designates a metallic member which is secured to the lower panel 11 of a piano at a point adjacent its upper 35 edge. The member 10 is provided with the offset ears 12 and 13 which are adapted to support a spring roller 14. This spring roller has mounted thereon a plurality of clips 15 which are adapted to embrace a rod 40 16 to which is secured the pad or shield 17 which may be of any desired, flexible material. The lower edge portion of said pad is provided with a rod 18, which is partially covered by the pad. The pad is provided 45 with a centrally arranged cut away portion 19, the portion of the rod adjacent said cut away portion, being covered with a resilient material 18'. A tab 20 is arranged cen-

trally on the rod in order to facilitate the positioning of the pad. 50

In placing the device in the position shown in Fig. 1, the pad is drawn downward against the tension of the spring roller until the cut away portion of said pad is in alignment with the pedals 21 of the instrument. 55 The lower edge of the pad is now forced toward the instrument, the covered portion of the rod 18 being allowed to rest against the under face of the said pedal and being held in engagement with said pedals by the 60 spring roller 14. When the instrument is not in use the pad is forced downward by means of the tab 20 and the rod 18 removed from engagement with the pedals. The tab is then released and the device assumes the 65 position shown in Fig. 3.

It will be seen from the foregoing that a device of this character will not only prevent the feet of the operator from coming in contact with the lower panel of the piano, but 70 the same is so constructed as to give the instrument a neat appearance. The fact that the rod 18 is covered with a resilient material at the point where it engages the pedals will assure an absolutely noiseless adjustment. The said resilient covering also preventing any sound which might arise from the depression of the pedals. 75

What is claimed is:

1. A piano protector comprising a bracket 80 arranged adjacent the pedals, a roller supported by said bracket, a shield of flexible material secured to said roller and adapted to be drawn down to the pedals of the piano, means for holding the roller yieldably with 85 the shield wound thereon, said shield being provided with a cut-away portion through which the pedals of the instrument may extend, and a rod incased by the lower edge portion of said shield, said rod being adapted 90 to engage the under face of said pedals, to hold the shield in an extended position against the tension of the roller-holding means.

2. A piano protector comprising a bracket 95 positioned upon the lower part of the front

of the instrument, a spring roller, mounted between the end portions of said bracket, a shield of flexible material secured to said spring roller, the lower portion of said shield being provided with a centrally arranged opening, a rod incased by the lower edge portion of said shield, the portion of said rod adjacent said opening, being pro-

vided with a resilient covering and a tab centrally arranged upon said rod.

In testimony whereof I affix my signature, in presence of two witnesses.

WILLIAM R. TURNER.

Witnesses:

NAT LARSON,
E. L. FURST.
